SCALP-TREATING DEVICE

Hillard M. Avery, Indianapolis, Ind.

Application September 1, 1949, Serial No. 113,563

13 Claims. (Cl. 128—64)

1

The present invention relates to a device for treating the scalp, and its primary purpose is to provide a device whereby controlled temperature conditions may be impressed upon the scalp. Additionally, it is an object of the invention to provide means for vibrating the device through which temperature control is attained. Still further, it is an object of the invention to provide means for impressing vibration upon the base of the user's skull and the adjacent muscles, tendons, leaders, and blood vessels, and upon the soft parts immediately adjacent the mastoid prominences of the user's temporal bones.

It is a further object of the invention to provide a device of the character described including means whereby water, or other fluid, may be caused to flow or circulate against the remote surface of a flexible diaphragm, impermeable to such fluid, which diaphragm is arranged to enclose the upper portion of the user's head during such flow.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a perspective view of a device constructed in accordance with my invention, in use position; and

Fig. 2 is a somewhat reduced longitudinal section through the device illustrated in Fig. 1.

Referring more particularly to the drawings, it will be seen that I have provided a coroniform frame comprising the elements 10 and 10' which elements, in the illustrated embodiment of the invention, are preferably pivotally connected, though the frame may be integral. A bladder, indicated generally by the reference numeral 11, and of general concavo-convex shape, is made up of separated elements 12 and 13, defining a hollow space therebetween. I presently believe that both of the elements 12 and 13 will preferably be formed of waterproof, flexible material, such as neoprene or some other suitable rubber substitute; though it may be desirable to make the element 12 of sheet metal or some other stiff, sturdy-bodied, water resistant material. The element 12 may, if desired, be rubber or rubberized fabric; but for reasons which will appear, the element 13 should be a readily flexible, waterproof material impervious to oils, alcohol, and the like.

2

The two elements 12 and 13 are joined, at the mouth of the concavo-convex bladder, as at 14; the joint defining a generally oval band somewhat larger than the average head contour. As shown, the element 13 is substantially hemispherical with the region of the joint 14 depending below the diametrical plane; and I presently believe such proportions to be optimum. The bladder is secured to the frame 10 at its mouth, as by rivets 16 or the like. In the illustrated embodiment of the invention, the forward portion of the bladder is free, to provide improved flexibility of the unit for accommodation of varying head sizes; but, in some instances, it may be desirable to secure the bladder to the entire perimeter of the coroniform frame.

The frame includes an arched transverse member 17.

A pad 15 of sponge rubber or similar material is located within the bladder near the center thereof, and is fixed to both walls 12 and 13 in any suitable fashion, as by cementing, vulcanizing, or the like; and a rivet or bolt 21 preferably secures the midpoint of the element 12 to the member 17. As shown, the rivet 21 may have its inner end embedded in the pad 15 to improve or establish the fixed connection between said pad and the element 12. It will be seen from Fig. 2 that a substantial area of the polar region of the element 13 is sealed to the pad 15, and that said pad constitutes a wall which renders the hollow interior of the bladder substantially annular.

At suitable points, preferably within the region traversed by the reinforcing strap 17 and on opposite sides of the pad 15, the bladder element 11 is provided with an inlet port 18, in which is arranged a nipple 19, and an outlet port in which is arranged a similar nipple 20. A flexible conduit 22 is connected with the nipple 19, and a similar flexible conduit 23 is connected with the nipple 20. Of course, in use, the conduit 22 is connected to a source of fluid of controlled temperature, while the conduit 23 leads to a point of discharge. Preferably, the conduits 22 and 23 will be provided with valving means such as, for instance, the hose clamps 24 and 25.

At each side of the frame 10 a guide member 26 is pivotally supported, as by means of a bolt 27. In the illustrated embodiment of my invention, each such guide member is formed with a guide-way 28 which opens, through a slot 29 through the outer surface of the guide element 26, for a purpose later to become apparent.

An electrically energized, low-frequency vibrator unit 30, which may be of conventional construction, includes two relatively movable ele-

3

ments. To yoke arms 31 and 32 are mechanically connected to one of said elements, while a post 33 is mechanically connected to the other of said relatively movable elements. A saddle 34 is carried by the post 33, the arrangement being such that, when the frame 10 is in position on the user's head, the saddle 34 will bear against the base of the user's skull and/or against the muscles, leaders, tendons and blood vessels immediately adjacent thereto. An electrical conductor cable 35 of conventional type is indicated, for the energization of the unit 30; and I have also shown an adjuster screw 36 whereby the frequency of vibration of the unit 30 may be tuned.

Obviously, each of the yoke arms 31 is adapted to be slidably received in the guideway 28 of one of the elements 26; and each such arm carries a clamp screw 37 whose shank projects through the slot 29 of the associated element 26, and which may be turned down to secure its associated arm 31 or 32 in any position of adjustment relative to the associated element 26. Obviously, such adjustment is provided in order to accommodate the saddle 34, in its position relative to the frame 10, to the particular shape of an individual user's head. I presently believe it to be desirable to mount a cushion 42 of sponge rubber or the like on the inner surface of the saddle 34.

Preferably, the saddle 34 supports two resilient leaves 38 and 39, one end of each leaf being anchored on the saddle, and the opposite end of each leaf carrying a member 40 of substantial mass. The arrangement of the elements is such that, when the treatment device is properly located on the user's head, the members 40 will bear against the soft parts of the user's neck immediately behind and below the mastoid prominences of the user's temporal bones, the supporting leaf for each member being somewhat flexed from its position of equilibrium.

I have found my treatment device to be highly effective in the application of tonics, lotions, or dressings to the hair. In use, I prefer to apply a suitable substance to the hair, distributing the substance thoroughly through the hair mass and against the scalp, and then to wrap the hair or scalp in a towel 41, or cloth cap. Now, I apply my treatment device, which, when the bladder is deflated, will clear the perimeter of the average user's head and rest, with that portion of the element 13 which is fixed to the pad 15, bearing on the top of the head. Now, the conduit 22 is connected to a source of, for instance, water of controllable temperature, and the conduit 23 is carried to a point of liquid disposal. The valve 24 is now opened, and the selected fluid will flow into, and fill, the cavity between the elements 12 and 13 of the bladder 11. Once the cavity has been filled, the valve 25 will be partially opened to permit circulation of fluid through the bladder cavity. Since flow through the outlet nipple is restricted, a fluid pressure sufficient to expand the bladder will be created therein; whereby the region adjacent the bladder mouth will be pressed closely into engagement with the perimeter of the user's head; and as the bladder thus expands, the user will adjust the device to a comfortable seat on his head such that, as indicated in Fig. 2, the device will be supported upon the inflated mouth region of the bladder, with the polar region of the bladder, occupied by the pad 15, out of contact with the crown of the user's head. The saddle 34 will now be adjusted to bear with desired pressure against the back of the head or neck.

4

Now, as liquid circulates through the bladder, the temperature of the entire region enclosed by the device will approach the temperature of the circulating fluid. Thus, if the circulating fluid is hot water, the pores of the scalp will be opened to assist penetration of the previously-applied dressing; circulation will be stimulated; and, in some instances, the dressing, or components thereof, will be volatilized. After a desired period of hot water circulation, I presently believe it to be desirable to circulate cold water through the bladder, thereby tending to close the scalp pores and, again, stimulating blood circulation. In some instances, it may be desirable to alternate hot and cold fluid circulation several times.

Beneficial effects can be obtained, through the control of the temperature by the flowing fluid, even in the absence of means for producing vibration. I presently believe, however, that these effects can be improved by energizing the unit 30 to vibrate the entire helmet and the saddle 34.

I have found my treatment device to be highly useful, additionally, in the treatment of headaches; and the resiliently-supported masses 40, bearing upon the muscles, leaders, tendons and blood vessels immediately adjacent the mastoid prominences, are particularly advantageous in this application of the device. The resiliency of the leaves 38 and 39 materially contributes to the application of proper modulating pressures to the affected parts; and the treatment tends to stimulate the blood flow to the head.

As I have indicated, substantial advantages may be attained through the use of the helmet, with its bladder arranged to permit the circulation of fluid of controlled temperature therethrough; even without the vibrator means; and substantial advantages may be attained by using the vibrating means without utilizing the fluid flow capacity of the illustrated invention. I presently believe, however, that the concurrent use of the two capacities of the unit produces optimum results in the application of dressings and the like to the hair and scalp.

I claim as my invention:

1. In a device of the class described, a coroniform frame, a hollow, concavo-convex bladder whose concave wall is readily flexible, the rim of said bladder being secured to said frame, an inlet port and an outlet port opening into and from the interior of said bladder, and flexible conduit means connected to each of said ports, said bladder being imperforate except for said ports.

2. The device of claim 1 in which said bladder is substantially part-spherical, including means interposed between and fixed to the bladder walls substantially at the center of said bladder and rendering the cavity within said bladder substantially annular, said inlet and outlet ports being peripherally spaced from each other.

3. The device of claim 2 in which said last-named means is a pad of water-resistant, softly resilient material.

4. The device of claim 1 including a nipple for each of said ports, and a transverse arched member carried by said frame and supporting said nipples.

5. The device of claim 1 in which said concave bladder wall is formed of waterproof material impervious to oil.

6. The device of claim 1 including a vibrator, and means providing a mechanical motion-transmitting connection between said vibrator and said frame.

7. The device of claim 6 in which said vibra-

tor includes a first part and a second part relatively movable with respect to said first part, one of said vibrator parts being mechanically connected to said frame, and the other of said vibrator parts being mechanically connected to a saddle which bears, when said frame is in position, on the back of a user's neck adjacent the base of the user's skull.

8. The device of claim 7 in which cushioning means is carried by that face of said saddle presented toward the user's neck.

9. The device of claim 7 including a resilient leaf anchored at one end on said saddle and supporting, at its opposite end, an element of substantial mass which, when said saddle is so placed, bears upon the soft parts adjacent the mastoid prominence of the user's temporal bone.

10. The device of claim 1 including a vibrator, a pair of yoke arms supportingly connected to said vibrator, a pair of elements on said frame and respectively arranged at opposite sides thereof, said yoke arms having a sliding association with said elements, respectively, and means for securing said yoke arms in any one of a plurality of positions of adjustment relative to said elements.

11. In a device of the class described, a coroniform frame, a vibrator, means providing a mechanical connection between said vibrator and said frame, and a saddle separately carried by said vibrator, said saddle bearing, when said frame is positioned on a user's head, against the user's neck adjacent the base of the user's skull.

12. The device of claim 11 including a resilient leaf anchored at one end on said saddle and supporting, at its opposite end, an element of substantial mass which, when said saddle is so placed, bears upon the soft parts immediately adjacent the mastoid prominence of the user's temporal bone.

13. In a device of the class described, a coroniform frame, a vibrator including a first part and a second part relatively movable with respect to said first part, one of said vibrator parts being mechanically connected to said frame, and the other of said vibrator parts being mechanically connected to a saddle which bears, when said frame is in position on a user's head, against the user's neck adjacent the base of the user's skull.
